SPRING COVER

George W. Crabtree, Cleveland Heights, Ohio

Application March 31, 1936, Serial No. 71,889

10 Claims. (Cl. 267—37)

This invention relates to improvements in covers for laminated vehicle springs and more particularly to a jointed section type of cover such as disclosed in my copending application 5 Serial No. 9,097, filed March 2, 1935.

It is among the objects of my invention to provide a metallic casing for a laminated spring which is simple and rugged in construction, will provide a lubricating means for the spring and 10 which will flex in response to spring movement and not interfere with the normal spring action. A further object of my invention is to provide a spring cover according to the preceding object having a plurality of body sections joined to each 15 other and a one-piece top for said sections which will facilitate the assembly of the cover upon the spring and insure that the top will not become separated from the sections during use. A further object of my invention is to provide a spring cover having bottom and top spring enclosing 20 portions in which the top portion is flexed intermediate its ends during assembly of the portions to provide a resilient latching union with the bottom portion when assembled. A further object of my invention is to provide a spring cover according to the preceding object in which the 25 top portion is provided with tongues adapted to enter apertures in the bottom portion when flexed during assembly and to be resiliently urged 30 into said apertures upon complete assembly of the top and bottom portions. It is also among the objects of my invention to provide a one-piece top unit for a spring cover having a plurality of curves intermediate its length to provide a 35 resilient latching of said top. A further object of my invention is to provide a metallic spring cover having a body section formed with inwardly turned prongs or tongues to engage a fabric liner or wrapper and prevent shifting or creeping of 40 said liner within the cover. Further objects and advantages relating to simplicity and economies of manufacture will appear from the following description and the accompanying drawings 45 wherein:

Figure 1 is an exploded perspective view of the elements forming the spring cover according to my invention;

Figure 2 is an elevation illustrating the position of the parts of the cover during assembly 50 upon a vehicle spring;

Figure 3 is a view similar to Figure 2 showing the spring cover as assembled and ready to use;

Figure 4 is a transverse sectional view taken along the line 4—4 of Figure 1;

Figure 5 is a transverse sectional view corre-

sponding to Figure 4 with the parts therein in their assembled position;

Figure 6 is an elevation on exaggerated scale with parts broken away illustrating the curvature of the top section with respect to the body 5 section of the cover;

Figure 7 is a view similar to Figure 6 except that the top and body sections are latched together.

Recent developments in the motor vehicle art 10 have been directed to improving the action of laminated leaf springs and the use of metallic spring covers and the advantages attendant upon their use have resulted in a general acceptance by the automotive industry of this type of cover. 15 The advantages of a cover comprised of jointed sections which will permit flexing of the cover in response to spring movement and the advantages of metallic cover with respect to its ability to retain a lubricant about the spring is 20 generally recognized. Among the difficulties encountered in connection with the use of certain types of metallic spring covers is that associated with the more or less permanent attachment of the cover to the spring, and associated with the 25 time and labor expended to attach such said types of covers to the spring. In the event that a spring leaf should break or that it is desired to add to the lubricant supply within the spring cover, it is important that the spring cover be 30 quickly and easily detached by manual manipulation, and yet the cover should not be open to the defect of inadvertent displacement by violent spring flexing.

Generally speaking, I have eliminated the objections noted in the above paragraph and have achieved the objects set forth above by the provision of a spring cover having a U-shaped body section indicated at 5 and a one-piece top or cap section indicated generally at 10. Preferably the 35 body section comprises a plurality (three in the illustrated embodiment) of U-shaped channel sections which are tapered throughout their length to correspond to the spring enclosed and which are proportioned at their ends to have an 40 overlapping or telescopic fit with each other. The U-shaped channel sections 6—7—8 in the illustrated embodiment are pivotally secured to each other by a rivet 26' or the like adjacent 45 their upper edges in their overlapping portions. 50 The lower walls of each of the channel sections through said overlapping portions are rounded upon an arc determined substantially by the radius from the pivot 26' to said lower wall. The rounded portion 29 on one end of the section 6 55

is compressed and slidably moves within the rounded portion **30** on the next adjacent section **7** and the other end of the section **7** is similarly rounded as at **31** to slidably rock or roll within the rounded joint portion **32** of section **8**. For convenience the section **8** will be referred to as the eye-end of the spring cover inasmuch as this end of the cover is positioned adjacent the shackle eye of the main spring leaf.

10 The free edges of the channel shaped sections **6**—**7**—**8** are preferably flanged as at **6a**—**7a**—**8a** and in positioning the body portion **5** of the spring cover about the spring said inturned flanges function to retain the body portion temporarily in position. This form of retention, however, is relatively impositive and facilitates the arrangement of a fabric grease retaining envelope. Preferably the grease retaining envelope or liner as used in my spring cover is provided with a 20 "self-forming" welt or grease retaining bead at its end portions as disclosed and claimed in my copending application No. 71,891 filed March 31, 1936.

To retain the fabric liner in its proper position with respect to the spring cover and the spring embraced thereby, the lower wall of the end body sections **6** and **8** are formed with one or more inwardly struck prongs or tongues **44**. The fabric liner is folded to embrace or 30 surround the spring and the prongs **44** on the metallic cover, gouge into the fabric, and insure that the liner will remain in position regardless of the flexing of the spring or shrinking tendencies of the fabric acting to disarrange the liner.

35 Alternatively the fabric grease retaining envelope may correspond to that disclosed in my Patent No. 1,981,448, November 20, 1934, or the temporary flange retention may facilitate positioning of lubricant retaining pads such as 40 closed and claimed in my copending application Serial No. 6,966, filed February 18, 1935. Those skilled in the art will appreciate that a spring cover constructed according to the present invention may be proportioned to receive and cooperate 45 with other types of lubricant retaining devices. The inturned flanges **6a**—**7a**—**8a** also permit slight adjustment of the spring cover body section **5** prior to and during the application of the top member **10**.

50 Preferably the top member **10** comprises a unitary longitudinal strip having downturned flanges, and may be economically stamped in one operation from sheet metal. During the stamping operations the top is provided with depressions such as **11a** and **12a** to define top portions **11**, **12**, and **13**. The flanges or side wall portions **14** and **16** of the top sections **11** and **13** respectively are each slotted from the end portion thereof as at **17** and **18** to provide latching 55 tongues **17a** and **18a** respectively. The latching tongues **17a** and **18a** are preferably rounded axially and transversely and thus cooperate to afford a snug resilient frictional fit within cooperating apertures **24** and **25** formed in the side walls of the cover body sections **6** and **8** respectively.

To insure a resilient latching of the top section of the cover to the body section, and thus provide a spring cover that will be silent under all 70 conditions of use, I prefer to form the portions **11**, **12** and **13** slightly arcuate with respect to their cooperating body sections **6**, **7** and **8**. The portion of the top section immediately adjacent the ribs **11a** and **12a** remain more or less flat throughout the formation and use of the cover,

whereas **11**, **12**, and **13** are arched as best shown on an exaggerated scale in Figure 6. In actual practice I have found that by arching their sections **11**, **12** or **13** so as to provide a space **C** of about $\frac{1}{16}$ of an inch, the cooperating struck-out latched portions **22**, **27** will be resiliently locked in position, and provide a space as at **C'** (Figure 7) of about $\frac{1}{32}$ of an inch. A further advantage growing out of the arcuate formation of the portions **11**, **12** and **13** is associated with the removal of the cover from the spring. For instance, by depressing the central portion above the interlocked latch **22**—**27** $\frac{3}{32}$ of an inch, the flange **15** may be forced outwardly by a screw driver or similar tool, and in this manner the entire top 15 may be quickly removed to facilitate lubrication or repair of the spring.

Since the top portion **10** of the spring cover and body section **5** in its assembled position are proportioned to have substantially the same axial extent, it will be observed that to position the latching tongues **17a** and **18a** in their cooperating apertures in the body portion, the entire top member **10** must be flexed so as to decrease its effective axial length as indicated in Figure 2. I have 20 found a convenient method of assembling the top member **10** upon the body section to comprise inserting the latching tongues, either **17a** or **18a**, in their respective apertures (see Figure 2) and then simultaneously flexing and moving the other end 30 of the top section downwardly to effect an insertion of the latching tongues at the other end of the body section. Subsequent to this action the top section may be pressed downwardly to force the flexed or center portion downwardly and effect 35 a secure latching engagement between the cooperating struck-out portions **26**—**21**, **27**—**22** and **28**—**23** formed on the body and top sections respectively (see Figure 3). As described above, each of the sections **11**, **12**, and **13** will be centrally depressed to latch them to their respective body sections. It will be observed that this method eliminates the need for any separate binding latches or the need for the peening over or clinching of interlocking elements subsequent to the positioning of the top or cap upon the body section. This feature presents an advantage commercially 40 over the prior art types of spring covers and assembly by reason of the labor and time saved on the assembly line in modern automotive production. 45

By following the foregoing construction and method of assembly I have found a spring cover constructed according to my invention to remain in position upon the spring and properly carry 55 out its normal function of providing a protective lubricant envelope for the spring in spite of violent spring flexing and abnormally adverse driving conditions.

Although I have described a preferred embodiment of my invention in considerable detail, I appreciate that those skilled in the art may effect variations and modifications therein without departing from the scope of the invention, and therefore I wish to be limited not by the specific disclosures made herein, but rather by the appended claims. 60

I claim:

1. A metallic cover for leaf springs comprising a series of U-shaped body sections arranged in an end-to-end telescoping relation and secured to each other in said telescoped portions to permit hinging movement between said sections, a top member for said body sections comprising a unitary strip provided with longitudinally extending 70

latching tongues, transverse apertures formed in the end sections of said series arranged to frictionally and resiliently hold said top carried latching tongues, a plurality of co-operating latching devices formed on said sections intermediate said tongues and apertures to prevent movement of said tongues with respect to said apertures.

2. A spring cover comprising a body portion formed of a series of inter-connected U-shaped sections proportioned to surround a part of a spring, a one-piece top portion having an axial extent corresponding to the length of the body portion, one of said portions provided with apertures adjacent its end, and the other of said portions provided with co-operating struck-out tongues adjacent its end, the axial distance between the free ends of the struck-out tongues and the axial distance between said apertures being unequal whereby assembly of said two portions necessitates the flexing of one of said portions to arrange said tongues within said apertures.

3. A metallic spring cover comprising a body portion formed of a series of inter-connected sections proportioned to surround a part of a laminated leaf spring, a top portion having an extent corresponding to the length of the body portion, one of said portions provided with apertures adjacent its end, and the other of said portions provided with co-operating struck-out tongues adjacent its end, the distance between the free ends of the struck-out tongues and the distance between said apertures being unequal whereby assembly of said two portions necessitates the flexing of one of said portions to arrange said tongues within said apertures.

4. A spring cover comprising a body portion formed of a series of inter-connected U-shaped sections proportioned to surround a part of a spring, the end sections of said series provided with apertures, a one-piece top portion having an extent corresponding to the length of the body portion, said top portion provided with tongues arranged to co-operate with the apertures formed in said body portion, the distance between the free ends of said tongues exceeding the distance between said apertures when in assembled position whereby assembly of the top and body portions necessitates a flexing of said top portion to facilitate the insertion of said tongues in said apertures.

5. A spring cover comprising a flexible body portion formed of a series of inter-pivoted U-shaped sections proportioned to surround a part of a spring, the end sections of said series provided with apertures, a one-piece flexible top portion corresponding in length to the length of the body portion, said top portion provided with tongues arranged to co-operate with the apertures formed in said body portion, the distance between the free ends of said tongues exceeding the distance between said apertures when in assembled position whereby assembly of the top and body portions necessitates a flexing of said top portion to facilitate the insertion of said co-operating tongues within said apertures.

6. A metallic spring cover comprising a body portion formed of a series of pivotally connected and telescopically over-lapped sections proportioned to embrace a laminated spring, a one-piece top portion having a length corresponding to the length of said body portion, apertures formed by substantially vertical slots adjacent rounded depressions near the opposite ends of one of said portions, axially extending co-operating tongues near the ends of the other of said

portions, the distance between the free ends of said tongues exceeding the distance between said apertures whereby flexing of one of said portions is required prior to the insertion of said tongues within their co-operating apertures.

7. A metallic spring cover comprising a body portion formed of a series of pivotally connected overlapped U-shaped sections, said sections formed with inter-engaging rounded parts in their overlapped areas, a one-piece top portion having a length corresponding to the length of said body portion, apertures formed by vertical slots and depressions near the opposite ends of one of said portions, co-operating tongues extending axially of the other of said portions, the distance between the free ends of said tongues exceeding the distance between said apertures when in assembled position whereby flexing of one of said portions is required to effect the insertion or removal of said tongues with respect to their co-operating apertures.

8. A spring cover comprising a body portion and a top portion, said body portion comprising a plurality of interconnected U-shaped sections, each of said sections provided with a substantially straight upper edge, said top portion comprising a like plurality of integral sections, each of said last named sections provided with a curved surface adapted to be disposed in alignment with said straight edge portions of the body sections, co-operating latching devices formed intermediate the ends of corresponding top and body sections whereby interengagement of said co-operating latching devices necessitates a depression or flexing of said top section.

9. A metallic cover for leaf springs comprising a series of U-shaped body sections arranged in an end-to-end telescoping relation and secured to each other in telescoped relation to permit hinging movement between said sections, a top member for said body sections comprising a unitary strip provided with longitudinally extending latching tongues, transverse apertures formed in the end sections of said series adapted to receive said longitudinally extending latching tongues and thereby secure said top member snugly against the body member at each end of the series, a plurality of co-operating latching devices intermediate said tongues and apertures to further secure said top member to said body member and prevent any separating movement between said members sufficient to permit said tongues to escape from said apertures by flexure of said sections.

10. A spring cover comprising a sheet metal body portion and a sheet metal top portion, said body portion including a plurality of interconnected U-shaped sections, each of said sections provided with longitudinally extending free edges, said top portion including a like plurality of integrally formed sections having the longitudinal edges thereof provided with a depending flange arranged to overhang the side walls of a corresponding body section, one of said portions provided with means adjacent the free edges of the sections thereof to space the opposed free edges of top and body in assembled relation, co-operating latching devices formed in corresponding top and body portions intermediate said means whereby interengagement of said co-operating latching devices necessitates a depression or flexing of one of said sections and said latching devices are held in interlocked relation by the resilience of said flexed metallic section.
